MUD GUN

Edgar E. Brosius, Pittsburgh, Pa.

Application October 18, 1933, Serial No. 694,065

7 Claims. (Cl. 266—42)

The present invention relates to so-called mud guns of the character utilized for stopping tapping holes or iron notches of blast furnaces at the completion of each furnace tapping operation.

Heretofore it has been common practice for a considerable period of time to operate mud guns by means of a piston actuated by steam. While such equipment has performed the function for which it is designed, it is, nevertheless, open to several objections. In the first place, it is not practical with steam pressure operated equipment, to have a steam generating equipment for each mud gun. This has necessitated the use, generally, of a centralized source of steam pressure connected with individual pieces of apparatus. Many pieces of equipment, not only mud guns, but other devices, are commonly connected to the central generating plant. With steam-operated installations not only has difficulty been encountered at times in the convenient location of the desired connections, but considerable difficulty has arisen from the tendency of steam to condense in the pipes and connections. This is particularly true where there are long steam lines and where the demand on the steam lines is relatively slight, as it is in the case of a single mud gun. More objectionable than this, however, is the difficulty either of assuring at all times a sufficient pressure condition to perform the plugging operation, or to prevent a dropping of the steam pressure before the operation has been completed. For example, in plugging tapping holes after a furnace tapping operation, it is obvious that it is desirable to provide equipment having such capacity that a plugging operation once started may be quickly completed. Not only this, but it is desirable that the plugging operation be accomplished under such conditions as to prevent the possibility of the furnace blowing outwardly through the mud gun barrel. When it is considered that it is of importance to be able to maintain full pressure within a blast furnace without fear of any possibility of damage by reason of such blowing out, it will be appreciated that not only is an effective pressure connection essential, but it is likewise essential that an operator be assured at all times that the steam is at a full pressure. It not infrequently happens that due to unusual demands on the steam generating unit, the pressure available for a given mud gun is reduced below that representing maximum efficiency of operation. In some cases, either due to failure of the steam generating equipment or

due to a heavy overload on such equipment, an operator is unable to perform or complete the tapping of a hole in a furnace.

With the present invention, the operator may be assured that at all times he can at least maintain such conditions as to hold the clay utilized for the plugging operation against the pressure within the furnace, even though it should be impossible, by reason of some mechanical failure, for him to complete the plugging operation.

In accordance with a preferred embodiment of my invention, there is provided in combination with the mud gun, a pressure supply means in the nature of a pump for circulating a liquid to the gun and effective for producing the necessary pressure conditions.

Moreover, with the present invention, the liquid utilized for effecting the operation of the mud gun is conserved. In this respect, it differs from steam-operated apparatus in which an exhausting operation is necessitated during each complete cycle, it not being feasible to reclaim the steam. Not only does such steam exhausting represent a waste, but it involves an element of danger, both from the standpoint of the temperature of the escaping steam and from interference with both vision and hearing occasioned while the steam is exhausting.

The invention may readily be understood by reference to the accompanying drawings, in which

Figure 1 is a longitudinal section through a mud gun used in accordance with my invention;

Figure 2 is a top plan view of the mud gun assembly;

Figure 3 is an end elevation of the arrangement shown in Figure 2;

Figure 4 is a side elevational view of a typical installation showing the mud gun in an operative position; and

Fig. 5 is a diagrammatic view illustrating a system of pressure connections for the gun.

Referring first to Figure 1, there is disclosed a plugging apparatus comprising a gun chamber or barrel 2 provided with a discharge nozzle or outlet 3. Clay within the chamber is adapted to be discharged through the outlet 3 by the operation of a piston or plunger 4 secured to the forward end of an operating rod 5, this rod having a piston 6 at its opposite end operating with a pressure cylinder 7. In Figure 1, the plunger 4 is shown at the forward limit of its ejecting stroke, whereas at the beginning of a plugging operation it normally would be at the right hand side of the cylinder 7 as viewed in Figure 1.

Intermediate the barrel 2 and the cylinder 7, there is provided a combined bearing and stuffing box assembly 8 of such construction as not only to effectively guide the rod 5 during its reciprocal movements, but also to shield the interior of the cylinder 7 against any appreciable leakage.

Mounted above the gun chamber or barrel and its hydraulic cylinder 7 is a clay reservoir 9 of cylindrical form. At the forward end of the reservoir 9, i. e., the left hand end as viewed in Figure 1, there is a port or opening 10 through which material can be forced from the reservoir 9 into the forward end of the barrel 2 and out the discharge member 3. At the forward end of the reservoir 9, i. e., the left hand end as viewed in Figure 1, there is a port or opening 10 through which material can be forced from the reservoir 9 into the forward end of the barrel 2 and out the discharge member 3. This opening 10 is preferably so located as to be adjacent the limit of travel of the plunger 4 in the gun chamber, whereby the plunger at the extreme forward limit of its travel acts to close the port 10 and cut off communication between the barrel 9 and the chamber 2. This is clearly shown in Figure 1 where the piston 4 is shown as blocking the passage 10.

Provided within the clay reservoir 9 is a second plunger 11 which is carried on the forward end of a rod 12, this rod being similar to the rod 5. On the opposite end of the rod 12 there is a piston 13 within a second hydraulic cylinder 14, the cylinder 14 being located above the cylinder 7. There is a combined guiding and packing assembly 15 at the end of the cylinder 14 similarly arranged to the combined guiding and packing element 8.

In the embodiment of the invention illustrated in the drawings, the two sets of cylinders are shown as having substantially parallel axes and being directly superimposed. This is particularly desirable in accordance with the present invention, not only for the reason that it gives a more compact structure, but for the reason that it lends itself admirably to the use of an individual portable source of liquid pressure supply. It also enables the use of comparatively long hydraulic pressure cylinders which may accordingly be of relatively small diameter, whereby it is possible to obtain a comparatively long stroke under extreme pressure conditions. In actual practice, I have found that desirable results are obtained by utilizing a fluid pressure of from 1400 to 1600 lbs. to the square inch. In accordance with the usual practice, the reservoir 9 may be provided with a hinged closure 16 which may be opened at the will of the operator to permit the reservoir 9 to be charged with clay. Upon completion of the charging operation the closure 16 may be fastened in position in any desired manner.

For filling the gun chamber 2, a suitable cap (not shown) may be placed over the outlet 3 to prevent the escape of clay therefrom. The plunger 11 may then be operated to force clay from the reservoir 9 into the gun chamber 2, the plunger 4 at this time being in its retracted position and the port 10 open. The gun chamber having been filled, a second charge of clay may then be put into the reservoir 9. When the two chambers 2 and 9 have been filled, the gun is ready for a plugging operation. When the plugging operation is to be effected, the gun is inclined at the position shown in Figure 3 in which position the discharge outlet 3 is adjacent the hole or nozzle to be plugged. The plugging may be accomplished either by first exhausting the charge within the gun chamber 2 or by exhausting the charge within the reservoir 9. In view of the prevailing tendency of operators to first empty the reservoir 9, this method of operation

will now be described. The piston 4 will be maintained in its retracted position at the extreme right hand end of the cylinder as viewed in Figure 1, and fluid under pressure is supplied to the cylinder 14. At this time, the piston 13, of course, will be at the right hand end of the cylinder. The fluid will act to move the piston toward the left. This will cause the plunger 11 to force the clay from the reservoir 9 through the port 10 out the discharge passage 3. After the reservoir 9 has been emptied, the plunger 11 will be kept in its projected position so as to prevent any substantial back-flow of clay through the port 10 and the plunger 4 will then be operated to expel the clay from the barrel 2 through the discharge member 3.

In actual practice, the capacity of the gun chamber plus the capacity of the reservoir is sufficient to effect a plugging operation of the usual tap opening. Should occasion require more clay, however, than that provided by the combined capacities of both the gun chamber and the reservoir, the plunger 11 may be moved to the right, while the plunger 4 is maintained in its projected position and additional clay can be introduced into the reservoir through the closure 16. Thereafter by slightly retracting the plunger 4 and advancing plunger 11, the additional clay charged into the reservoir may be forced out into the tap hole where the plugging is taking place.

The use of the plunger 4 as a gate or valve for closing the opening 10 when the plunger is in its forward position enables a re-charging operation of the character referred to, while maintaining the necessary pressure on the clay previously ejected into the opening to prevent the clay from blowing out through the barrel of the mud gun. This, of course, assures that a sufficient constant pressure be maintained in the cylinder 7 at all times to prevent any backing up of the clay due to the back pressure in the furnace. In accordance with the present invention, the pressure for operating the pistons 6 and 13 is obtained by the use of a fluid pressure pump, such for instance, as one which is commercially sold by American Fluid Motors Co. under the trade-mark "Hele-Shaw" and which is shown in Figure 7 of my Patent 1,930,467, dated Oct. 17, 1933. Such pumps may be operated to maintain a substantially constant fluid pressure with a variable output of the fluid. By reason of the provision of a pump of this character, a volume of fluid under pressure can be supplied to the cylinders 7 and 14 to operate the pistons 6 and 13 at the desired rate of speed and the pressure can be held constant.

As is customary in the art, one of the furnace columns designated 17, is provided with a suitable bracket 18, this bracket providing a pivotal mounting for a gun boom 19, the boom being adapted to swing about the axis of a pivot pin 20 which pin is carried on the bracket 18, the axis of which is substantially parallel to the axis of the furnace column 17.

Depending from the outer end of the boom is a gun bracket 21 rigidly secured to the boom and provided at its lower end with an anti-friction roller 22. Secured to the gun is a trolley rail 23 under which the roller 22 passes and with which the roller engages, this roller and trolley rail cooperating to permit relative movement between the gun bracket 21 and the gun. It also permits the gun to be dipped or tilted from a horizontal

position to an inclined position as shown in Figure 3.

Secured to the furnace column 17 is a strap 24 having clips 25 which cooperate with an exhaust pipe 26, a pressure supply pipe 27 and a pressure supply pipe 28. As shown in the diagram in Figure 5, the exhaust pipe 26 is common for both cylinders 7 and 14. The pipe 27 connects with the cylinder 7 and the line 28 connects with the cylinder 14. The clips 25 hold the respective pipes against movement relatively to the column, and each of the pipes is provided with one portion 29 of a flexible joint, the axis of which coincides with the axis of the pin 20. Cooperating with the portions 29 are other portions 30 carried, respectively, on pipe sections 26', 27' and 28'. These pipe sections are so shaped as to extend upwardly along the furnace column 17 into position adjacent one side of the boom 19, and they are secured to the boom by a second strap 31.

Fastened to the end of the boom 19 is a plate 32 having openings through which the pipe sections 26', 27' and 28' extend. The outer end of each of these pipe sections is provided with one portion 33 of a flexible joint, the other portion 34 of which is carried by pipe sections 26'', 27'' and 28'', respectively. These last mentioned pipe sections extend downwardly different distances and are provided on their lower end with portions 35 of flexible couplings, the other portions 36 of which are carried, respectively, by pipe sections 26''', 27''' and 28'''.

The pipe section 28''' communicates with one port in the casing of a four-port, two-way valve 37 which controls the hydraulic cylinder 14. The valve 37 is provided with side portions having a connection 38 to the rear end of the cylinder 14 and a connection 39 to the front of said cylinder whereby with the valve 37 in one direction, fluid may be delivered to one end of the cylinder 14, while with the valve in the opposite direction, fluid may be delivered to the other end thereof.

The pressure pipe section 27''' is connected to one port of a four-port, two-way valve 40 similar to the valve 37 and having an outlet port communicating through a connection 41 to the rear of the cylinder 7, and a second port communicating through a connection 42 to the front end of the cylinder 7.

The valve 37 has an exhaust connection 43 communicating with an exhaust connection 44 provided for the valve 40, these two exhaust connections communicating with the exhaust pipe section 26'''.

The valves 37 and 40 are normally so set that fluid under pressure will be delivered to the rear ends of the cylinders 7 and 14 upon the delivery of fluid under pressure to the pressure lines 27 and 28. The pressure line 28 is provided with an oil lubricator 45 while the line 27 is provided with a similar oil lubricator 46, these two lubricators being effective for delivering a predetermined amount of oil to the pressure lines for specially lubricating the various flexible joints and the valves. Where the system is using as a fluid an oil which is also a lubricant, these special lubricators 45 and 46 may be omitted. The pressure line 27 is provided with a globe or other manually operable valve 47 and the line 28 is similarly provided with a valve 48. These two lines both communicate with the outlet 49 of a suitable fluid pressure pump 50 of the output variable pressure type above referred to. This pump is provided with an inlet connection 51 leading from a fluid reservoir 52. The exhaust line 26 discharges

fluid into this reservoir 52. There is thus provided for operating the cylinders a closed fluid circulating system in which the necessary operating pressure can be built up and maintained to effect the necessary operation of the mud gun. 5

The construction and relationship of the various universal joints 29 and 30 are such that free swinging movement of the boom 19 is permitted for bringing the gun either into cooperative relation to the furnace or permitting movement thereof in the opposite direction. The flexible joints 33-34 and 35-36 are respectively so located that movement of the character described between the roller 22 and the trolley rail 23 is not interfered with, the axes of the various flexible joints coinciding in each instance substantially with the axes of movement of the various parts of the boom and gun assembly. 10 15

The control valves 48 and 49 may be located at a suitable distance from the gun itself and preferably adjacent an operator's station. It has been found desirable with this thought in mind, to mount them on the gas house wall whereby an operator out of the zone of intensive heat may effectively control the supply of operating liquid at will to either the hydraulic cylinder 7 or the cylinder 14.

As before stated, the capacity of these cylinders is such that ordinarily the clay held therein will be more than sufficient for effecting a plugging operation. The plugging operation having been completed, the gun is swung to its inoperative position and the valves 37 and 40 manually controlled as required to effect a re-charging of the gun cylinder 2 and the reservoir 9, as before described.

While I have not herein shown the splasher cylinder, the crane operating cylinder or the clamping cylinder, which are usually provided with equipment of this character, as is well known to those skilled in the art, it will be understood that such cylinders may be provided in accordance with the usual practice.

With the construction herein shown, by closing one or the other of the control valves 48 and 49, 45 the pistons 6 and 13 may be absolutely locked in any position to which they may have been moved to thereby hold the clay in position and prevent blowing out of the furnace. Such an operation is not possible in a steam-operated unit, 50 for example, in which upon failure of the pressure supply, there is no means of holding the cylinders against movement, inasmuch as the steam previously admitted to the cylinders rapidly condenses to hold the same therein. Moreover, very gradual movement of the plungers may be effected, whereas with steam-operated units it is difficult to effect small increments of movement, particularly in retracting the plungers. The particular advantage of the invention can 55 be seen in the case previously described where the charge of both the barrel 2 and the barrel 9 are insufficient to plug the tap hole in the furnace. I have previously pointed out that in this case the plunger 11 is retracted while the plunger 65 10 is held in the projected position. Thus the plunger 4 prevents the clay from blowing back. It can be held in this position indefinitely because of the fact that there is no condensation or loss of the fluid in the closed circulating system. 70 After the plunger 11 has been retracted, additional clay can be put into the reservoir 9. With the present invention it is thus possible to give a very slight retracting movement to the plunger 4 sufficient to uncover the port 10 and then hold 75

the plunger in this intermediate slightly retracted position while the additional clay is forced by operation of the plunger through the opening 10. With the steam operation of a similar unit, difficulty is encountered first in retracting the plunger 4 to a limited extent and then in holding the plunger 4 in the intermediate retracted position. Either the steam pressure tends to propel the plunger 4 to the full forward limit of its travel, or is insufficient to prevent further back travel of the plunger 4 under the pressure of the clay. Therefore, the fluid circulating system of the present invention has peculiar adaptability to a two-cylinder unit of the type herein specifically described.

While I have herein illustrated certain preferred embodiments of the invention, it will be understood that changes in the construction and operation of the various parts may be made without departing either from the spirit of the present invention or the scope of the broader claims.

I claim:

1. A mud gun system comprising a gun having a plunger, an operating piston and cylinder for the plunger, a fluid pressure reservoir, a pump, and a closed liquid circulating system with valves for alternately connecting either end of the cylinder with the pump or the reservoir.
2. A mud gun system comprising a gun having a plunger, an operating piston and cylinder for the plunger, a fluid pressure reservoir, a variable output constant pressure maintaining pump unit, and a closed circulating system for alternately connecting either end of the cylinder with the pump or the reservoir, valve means in said system for selectively connecting either end of the cylinder with the pump or reservoir, the system also having valve means for holding fluid under pressure in the cylinder.
3. A mud gun system comprising a gun having a plunger, an operating piston and cylinder for the plunger, a fluid pressure reservoir, a pump, and a closed circulating system of valves for alternately connecting either end of the cylinder with the pump or the reservoir, the valves being effective also for holding a fluid pressure in either end of the cylinder to definitely lock the cylinder against movement.
4. A mud gun system comprising a gun having

an adjacent barrel and reservoir, the reservoir communicating with the barrel, a plunger in both the barrel and the reservoir, a piston connected with each plunger and a cylinder for each of said pistons, a fluid pressure pump, a liquid reservoir connected with the pump, and piping including valves for connecting each end of each cylinder with the pump and with the liquid reservoir.

5. A mud gun system comprising a gun having a barrel and a reservoir communicating therewith, the barrel and the reservoir being adjacent, a plunger in both the barrel and the reservoir, a piston connected with each plunger and a cylinder for each of said pistons, a liquid reservoir, a pump connected with the liquid reservoir, and a circulating system including valves for connecting either end of each cylinder with the pump or with the liquid reservoir at will.

6. A mud gun system comprising a gun having a barrel and a reservoir communicating therewith, the barrel and the reservoir being adjacent, a plunger in both the barrel and the reservoir, a piston connected with each plunger and a cylinder for each of said pistons, a liquid reservoir, a pump connected with the liquid reservoir, and a circulating system including valves for connecting either end of each cylinder with the pump or with the liquid reservoir at will, the valves of the system also being arranged to hold the liquid under pressure in the cylinders and thereby effectively lock the cylinders in a given position.

7. A mud gun system comprising a gun having a barrel and a reservoir communicating with the barrel, a plunger in the barrel and a plunger in the reservoir, a separate piston for each of said two plungers and a cylinder for each of said pistons, a liquid pump, a liquid reservoir connected to the inlet side of the pump, a closed fluid circulating system leading from the liquid reservoir to each end of each cylinder and from the pump to each end of each cylinder, valve means in the system for cutting off communication from the outlet of the pump to either cylinder, and valve means in the system for alternately connecting each end of each cylinder with the pump and with the liquid reservoir.

EDGAR E. BROSIUS.
